DRIVE MECHANISM FOR SHEET COATING APPARATUS

Henry S. Bell, Wheeling, W. Va., and Hans E. Melin, Youngstown, Ohio, assignors to The Wean Engineering Company, Inc., Warren, Ohio, a corporation of Ohio

Application October 25, 1940, Serial No. 362,756

4 Claims. (Cl. 91—12.7)

This invention relates to apparatus for applying a protective coating to metal sheets, and specifically to machines for galvanizing ferrous sheets.

Galvanizing machines as generally constructed heretofore have included feed-in or entry rolls, bottom rolls and exit or finishing rolls with means for driving the several sets of rolls. Galvanizing machines must be removed occasionally from the spelter pot on which they are normally disposed. It is necessary, furthermore, to change the exit or finishing rolls at relatively short intervals, for cleaning, because they tend to pick up impurities from the bath which mar the surface of the sheets being coated.

In one commonly used form of galvanizing machine, the mechanism for driving the several sets of rolls is disposed on a base adjustable laterally of the spelter pot and includes drive shafts normally disposed in driving relation with the rolls. The base and the driving mechanism thereon are moved away from the pot as a unit and the driving connections with the rolls of the machine are broken when it is desired to remove the machine from the pot or to change the finishing rolls. This is a tedious operation, requiring a considerable amount of time. Careful alinement of the driving gears is necessary, furthermore, after the roll change has been made, in order to insure proper coaction without excessive wear. A further objection to the construction and practice described is that the retraction of the driving mechanism as a unit involves stoppage of the bottom rolls and the fact that difficulty may be experienced in again starting these rolls after a prolonged stoppage.

We have invented a novel coating apparatus including means whereby the aforementioned objections to previous constructions are entirely avoided. In a preferred embodiment of the invention, we provide a drive for the finishing rolls of a galvanizing machine which includes a member movable independently of the mechanism for driving the entry and bottom rolls, whereby the finishing roll driving connections may be broken to facilitate changing the finishing rolls, without stopping the other rolls or involving any adjustment of their driving mechanism. More specifically, we provide a driving shaft having a gear adapted to mesh with a gear on one of the finishing rolls, and means mounting the shaft for axial movement into and out of cooperative relation with the gear on the roll. Further novel features and advantages of the invention will become apparent during the following detailed description

of the preferred embodiment which refers to the accompanying drawings. In the drawings:

Fig. 1 is a partial plan view of a galvanizing machine and driving mechanism therefor, certain portions thereof being omitted for the sake of clearness;

Fig. 2 is a longitudinal section through the machine along the plane of line II—II of Fig. 1, showing the driving mechanism in elevation;

Fig. 3 is a partial section taken along the plane of line III—III of Fig. 1; and

Fig. 4 is a partial section taken along the plane of line IV—IV of Fig. 3.

Referring now in detail to the drawings, a galvanizing apparatus indicated generally at 10 includes entry rolls 11, bottom rolls 12 and exit or finishing rolls 13 journaled in side frames 14. The side frames 14 are normally disposed on a spelter pot 15. Guides 16 cooperate with entering rolls and guides 17 and 18 are disposed between adjacent sets of rolls in the known manner. A spangle-forming conveyor 19 receives sheets discharged by the exit rolls 13. This construction is largely conventional and forms no part of the present invention.

The mechanism for driving the rolls of the galvanizing machine, with which our invention is more particularly concerned, is indicated generally at 20 and is mounted on a base 21 adjustable laterally of the pot 15 along rails 22 of a sub-base 23, by means of an adjusting screw 24.

A motor 25 drives a shaft 26 journaled on the base 21 in the bearing 27, through a speed-reducing gear 28. A shaft 26 drives the entry rolls 11 through a chain-and-sprocket drive 29 and flux rolls (not shown) through a similar drive 30.

A motor 31 drives a shaft 32 journaled in a bearing 33 on the base 21, through a speed-reducing gear 34. The shaft 32 drives the bottom rolls 12 through bevel gearing 35, a generally vertical shaft 36 journaled in the side frame 14 adjacent the driving mechanism 20, and a worm drive 37.

A motor 38 drives a shaft 39 journaled in a bearing 40 on the base 21 through a speed-reducing gear 41. The shaft 39 is provided with a gear 42 normally meshing with a gear 43 on the neck of one of the rolls 13.

Referring more particularly to Figs. 3 and 4, the speed-reducing gear 41 includes a worm shaft 44 to which the shaft of the motor 38 is directly coupled, the worm shaft being journaled in suitable bearings formed in the housing 45 enclosing the speed-reducing gear. A worm 46

on the shaft 44 meshes with a worm wheel 47. The worm wheel 47 is secured to a sleeve or quill 48 journaled in the housing 45 in bearings 49.

The end of the shaft 39 remote from the gear 42 is splined in the quill 48, i. e., is slideable longitudinally therein but is held against rotation relative thereto by a key 50. The extreme end of the shaft, furthermore, has a reduced portion 51 with which a shifter head 52 cooperates. The head 52 includes a bearing 53 and a shell 54.

A lever 55 is pivoted to the base 21 at 56 and to the shell 54 at 57. The lever is normally locked in the position in which it is illustrated in solid lines by a pin 58 adapted to be inserted through a hole in a bracket plate 59 secured to the housing 45, when a hole 60 in the lever is properly aligned therewith. On removing the pin 58, however, and swinging the lever 55 to the position shown in chain lines, the shaft 39 is moved axially and the gear 42 is moved out of 20 driving relation with the gear 43.

The bearing 40 is slideable on the base 21 to permit axial movement of the shaft 39. As shown in Fig. 4, the bearing 40 is movable along dove-tailed ways 61, being held thereon by a 25 gib 62.

In the operation of the apparatus described, the motors 25, 31 and 38 are normally energized to drive the rolls 11, 12 and 13 at substantially the same peripheral speed. This three-motor 30 drive for the rolls of a galvanizing machine is also illustrated and claimed in the copending application of Donald A. McArthur, Ser. No. 333,476, filed May 6, 1940. Sheets fed between the guides 16 are passed through the molten zinc in the spelter pot 15, passing between the several sets of rolls successively and being ultimately discharged onto the spangle-forming conveyor 19.

When the apparatus has been in operation for such length of time as to require a change of the finishing rolls 13, the lever 55 is shifted from its solid line position shown in Fig. 3 to its chain line position after removal of the pin 58. As already described, this shifts the gear 42 out of driving relation with the gear 43. The rolls 13 are thereby stopped and the rolls are free for removal and replacement. The driving relation between the members of the bevel-gear drive 35 is not disturbed so the bottom rolls 12 may be driven continuously during the changing of the finishing rolls, thereby obviating any difficulty such as has been encountered heretofore in attempting to restart the bottom rolls after they have remained stationary for a substantial period. As soon as a new set of finishing rolls 13 has been put in place, the lever 55 is restored to the position shown in solid lines whereupon the gear 42 again meshes with the gear 43 on one of the rolls of the new set. The motor 38 is stopped before the gears 42 and 43 are put in mesh and may be stopped before the shaft 39 is initially retracted to permit removal of the used finishing rolls. Since the shaft 39 is movable only along its own axis, there is no possibility that the gear 42 will fail to be in proper alignment for meshing smoothly with the gear 43.

It will be apparent from the foregoing that the invention is characterized by important advantages over galvanizing machines as made heretofore. The ease with which the driving connections to the finishing rolls may be broken

and restored greatly expedites the operation of changing the finishing rolls. The saving made possible thereby, in the form of increased production, may be readily appreciated from the fact that the finishing rolls have to be changed at least once every eight hours and sometimes more frequently. Not only is a considerable saving of time effected but the actual operations necessary for changing the finishing rolls are much simpler with the improved apparatus of our invention than with the conventional construction previously employed. The advantage of avoiding the danger of "freezing" of the bottom rolls has already been referred to.

Although we have illustrated and described herein but a preferred embodiment of our invention, it will be recognized that changes in the construction and arrangement disclosed may be made without departing from the spirit of the invention or the scope of the appended claims.

We claim:

1. A drive for the exit rolls of a sheet-feeding rig adapted to be disposed on a pot containing molten coating metal, said drive comprising a motor, a shaft extending over one of said rolls and geared thereto, and normally preventing removal of said rolls, gearing connecting said motor and said shaft, and means mounting said shaft for sliding movement relative to said gearing whereby it may be retracted relative to said motor and gearing to clear said rolls and facilitate changing thereof.

2. Drive mechanism for a coating machine including feed-in rolls, bottom rolls and exit rolls, said mechanism comprising a shaft adapted to drive each set of rolls, means driving the shafts and gearing between said means and shafts, the exit-roll drive shaft extending above one of the exit rolls, and means mounting the exit-roll drive shaft for axial movement whereby it may be shifted to clear the exit rolls and facilitate changing thereof without necessitating stoppage of the bottom rolls.

3. Drive mechanism for a coating machine including feed-in rolls, bottom rolls and exit rolls, said mechanism comprising a shaft adapted to drive each set of rolls, a base on which said shafts are journaled, driving means for said shafts on said base, said base being retractable to move said shafts out of driving relation with said rolls, gearing between said shafts and said driving means, the gearing of the exit-roll drive shaft including a gear wheel through which the exit-roll drive shaft is slideable axially whereby it may be moved out of driving cooperation with the exit rolls independently of said other shafts.

4. Drive mechanism for a coating machine including feed-in rolls, bottom rolls and exit rolls, said mechanism comprising a shaft adapted to drive each set of rolls, a base on which said shafts are journaled, driving means for said shafts on said base, said base being retractable to move said shafts out of driving relation with said rolls when it is desired to remove all said rolls, and means mounting the exit-roll drive shaft for axial movement whereby it may be shifted out of driving relation with the exit rolls independently of the other shafts, when it is desired to change the exit rolls without stopping the bottom rolls.

HENRY S. BELL.
HANS E. MELIN.
